UNITED STATES PATENT OFFICE.

FRANK THUERINGER, OF SAUK RAPIDS, MINNESOTA.

WRENCH.

1,406,106.

Specification of Letters Patent. Patented Feb. 7, 1922.

Application filed November 24, 1919. Serial No. 340,184.

To all whom it may concern:

Be it known that I, FRANK THUERINGER, a citizen of the United States, residing at Sauk Rapids, in the county of Benton and 5 State of Minnesota, have invented certain new and useful Improvements in Wrenches, of which the following is a specification.

This invention relates to wrenches, and the primary object of the invention is to 10 provide an improved wrench, which can be adjusted by the closing movement of the hand, so that the jaws of the same can be quickly adjusted to take hold of an article and to obviate the necessity of turning adjusting nuts or screws to get the desired 15 adjustment.

A further object of the invention is to provide means for locking the movable jaw in adjusted position when desired by the 20 user.

A further object of the invention is to provide a quick adjusting wrench having an improved lock for the movable jaw thereof, which is normally held in an inoperative 25 position, so that the jaws can be held in an adjusted position with the work by the hand of the operator, thereby permitting the quick operation of the tool for light work.

A still further object of the invention is to 30 provide an improved wrench of the plier type having a wide range of adjustment and having the parts thereof so constructed as to provide a tool which will be durable and efficient in use, one which is simple and easy 35 to manufacture, and one that can be placed upon the market at a reasonable cost.

Other objects of the invention will appear in the following detailed description taken in connection with the accompanying 40 drawings, forming a part of this specification, and in which drawings:

Figure 1 is a perspective view of the improved wrench.

Figure 2 is a perspective view of the same 45 with one of the plates removed, and

Figure 3 is a detail perspective view of one of the plates, showing the inner side thereof.

Referring to the drawings, in detail, 50 wherein similar reference characters designate corresponding parts throughout the several views, the letter A indicates the improved wrench, which includes the frame sections B and C, carrying the rigid jaw D; 55 the movable jaw F; the operating handle G, and the lock H.

The frame sections B and C are identically formed and are adapted to be placed one upon the other, when the device is assembled, and each includes the arcuate 60 handle portion 5 having the laterally projecting head 6 formed on the outer terminal thereof. The inner face of the head portion 6 and the adjacent portion of the handle portion 5 is cut away to form a 65 pocket 7 for the movable jaw F and the inner portion of the operating handle G, when the sections are placed one upon the other. The head portion 6 of the sections B and C are cut away in such a manner as to define side walls 8 and 9, which extend flush with the outer edges of the head. The upper edge of each head portion 6, at one end thereof, is provided with an upwardly extending extension 10, which forms the rigid 70 jaw D.

The movable jaw F includes the relatively long laterally projecting shank 11, which as stated is adapted to be positioned in the pocket 7 when the sections B and C are 80 placed together, and the sections form a guide for the same. The side faces of the shank 11 are reduced to form shoulders 12, which slidably engage the outer edges of the sections B and C. One end of the shank 85 is provided with the outwardly extending jaw 13, and the outer surfaces thereof extend in the same plane with the movable or rigid jaw D. The inner faces of the pocket 7 have aligned guide grooves 14 formed 90 therein, which extend transversely across the head. The grooves 14 are adapted to slidably receive the longitudinally extending ribs 15 formed on the opposite faces of the shanks 11. The ribs 15 and the grooves 14 95 provide means for guiding the movable jaw 13 in its sliding movement transversely across the head toward or away from the rigid jaw D. The outer end of the shank 11 remote from the movable jaw 13 is provided with a rearwardly extending lug 16, which is adapted to engage the outer surface of the side wall 8 of the pocket, to limit the inward movement of the jaw section, and thus prevent displacement thereof. The 100 inner edge of the shank 11 is provided with a rack bar 17, the teeth of which are adapted to be engaged by the adjusting means G.

The adjusting means G include a flat body 18, having the circular head 19 110 and the tangentially extending outwardly curved handle 20 which is adapted to co-

operate with the handle 5 in forming means, for adjusting the wrench. The circular head 19 is adapted to be positioned in the pocket 7 and the same is provided with an opening 21, which is adapted to receive the pivot pin 22, which is adapted to be threaded into openings 23 formed in the companion sections B and C. The pin 22 forms means for pivotally securing the member G in position and for holding the sections B and C in assembled position. The forward edge of the circular head 19 is provided with relatively large teeth 24, which are adapted to mesh with the teeth of the rack bar 17 and thus it will be seen that when the member 20 is operated, the movable jaw section will be moved toward or away from the rigid jaw D, according to the direction in which the member is moved. The side face 20 of the circular head 19 is provided with relatively small teeth 25, which form means for cooperating with the lock structure H for holding the head 19 against movement when the jaw 14 in its adjusted position 25 against work which is relatively hard to turn. The relatively small teeth 25 are substantially in the same arc with the relatively large teeth 24, and the teeth 24 and the teeth 25 are substantially concentric with the axis 30 of the opening 21. A leaf spring 26 is secured to the opposite side of the circular head 19 from the small teeth 25 by a screw or other suitable fastening element 27, and the free end of the spring is bent outwardly 35 and is adapted to engage the side wall 8 for normally holding the handle 20 toward the handle 5, so that the movable jaw structure F will be held in a closed position with relation to the rigid jaw structure D.

40 The lock structure H includes a pawl 28 having a toothed end 29 which is adapted to engage the relatively small teeth 25. The pawl 28 is provided with an opening 30 which is adapted to receive the pivot pin 31, 45 which is threaded into the sections B and C and forms additional means for holding the sections in assembled position. The toothed end 29 of the pawl is normally held out of engagement with the teeth 25, by means of 50 an expansion coil spring 32, which is seated in recesses 33 formed in the handle portion 5 of the sections B and C and which extend inwardly from the pocket 7. A thumb piece 34 is adapted to engage the pawl 28 on the 55 opposite side of the pivot pin 31 from the spring 32, and the same is adapted for swinging the pawl on its pivot when it is desired to move the toothed end thereof into engagement with the relatively small teeth 60 25. The thumb piece 34 includes a cylindrical shank 35 which is slidably mounted in an opening formed in the raised portion 36 of the face of the section C. A recess 36^a is provided in the section B to accommodate the portion 36, when the sections B and C

are clamped together. The opening in the portion 36 communicates with the pocket 7 and the outer edge of the handle 5. The shank 35 may be threaded into engagement with the pawl 28 and the same has the outer end thereof provided with a flat head 36^b. The sections 10 of the rigid jaw sections B and C and the outer terminals of the handle portion 5 of the sections B and C are provided with suitable openings 37 for the reception of screws or other fastening elements 38. The inner surfaces of the rigid jaw D and the movable jaw F is serrated or roughened to provide teeth 39 so that a firm and positive grip may be obtained 75 on nuts, pipes, or other work.

In operation of the improved wrench, the jaws D and F are placed in engagement with the work, and the handles 20 and 5 are then grasped by the hand of the user and 80 brought toward each other which will forcibly bring the jaws into gripping contact with the work. If the work is relatively easy to turn, it is not necessary to use the lock structure H. However, if the work is 85 hard to turn, the thumb is pressed on the flat head 36^b so as to move the thumb piece 34 inwardly which will swing the pawl 28 on its pivot and force the toothed end 29 thereof into engagement with relatively 90 small teeth 25 on the circular head 19, thus preventing movement of the adjusting means G, and consequently of the jaw F.

From the foregoing description it can be seen that an improved tool of simple and 95 durable construction is provided of the plier type which will permit the quick and ready grasping of the work.

Changes in details may be made without departing from the spirit or scope of my 100 invention; but,

I claim:

1. A wrench comprising a frame structure formed of two sections and having a rigid jaw and rigid handle thereon, the facing portions of said sections recessed to provide a pocket, a movable jaw, having a laterally projecting shank disposed within the pocket portion of said frame section, an adjustable handle pivotally connected with 110 in the pocket portion of said frame and having a handle projecting therefrom adapted to cooperate with the rigid handle of said frame, for moving the movable jaw, a pawl carried by said frame section, and means 115 positioned exteriorly of the frame section for operating said pawl to engage the movable handle, to lock the movable jaw in a predetermined position.
2. In a wrench, the combination, of a 125 frame structure comprising a pair of rigid sections having rigid jaw sections thereon, said sections having handle portions thereon and having the facing sides thereof recessed to provide a pocket, a movable jaw 130

- section having a laterally projecting shank provided with longitudinal ribs adapted to engage the rigid frame sections within the recessed pocket provided thereby, and
- 5 adapted for sliding movement for adjusting the degree of proximity of said movable jaw with respect to the rigid jaw, an adjusting handle, and locking means carried by said rigid frame section and adapted to lock the
- 10 movable jaw in a predetermined position with respect to said rigid jaw.
3. A wrench, comprising, in combination, a frame section, comprising a pair of sections, each of said sections having arcuate handles, lateral heads formed integral with said handles, and projecting jaw sections formed upon each of said heads, to form a rigid jaw, the facing sides of said lateral heads and handles being recessed to provide
- 15 a pocket and having guiding grooves therein, a movable jaw having a laterally projecting shank thereon adapted for positioning in the pocket provided by said frame section and having guide ribs thereon for
- 20 positioning within the guide grooves of said frame section, and provided with a toothed rack bar, an adjusting handle pivoted within the pocket formed by said frame section comprising a flat body having a circular
- 25 head, said circular head being provided forwardly with relatively large teeth adapted to engage the teeth of said rack bar for adjusting the position of said movable jaw upon movement of the adjusting handle, the
- 30 side of said circular head being provided with relatively small teeth, a spring for normally maintaining said movable jaw in closed position, a lock structure comprising a pawl having relatively small teeth thereon
- 35 adapted to engage the small teeth of the adjustable handle, and a thumb piece carried by said frame structure and adapted for adjustment to move said pawl into engagement
4. A wrench comprising a frame, a rigid jaw formed on one end of the frame, a rigid handle formed on the opposite end of the frame, an adjustable jaw slidably mounted transversely of the frame for cooperation with the rigid jaw, an operating handle carried by the frame and operatively connected to said movable jaw for permitting the moving thereof into clamping position in relation to the rigid jaw, locking teeth formed on said handle, a locking pawl pivotally carried by the frame arranged to engage the teeth, spring means normally holding the pawl out of engagement with the teeth, and a thumb piece for moving the pawl against the tension of the spring means into engagement with the teeth whereby movement of the operating handle will be prevented and the jaw held in its adjusted position.
5. A wrench comprising a frame having a laterally projecting head, a forwardly extending rigid jaw formed on one end of the head, a rearwardly projecting handle formed on the opposite end of the head, a sliding jaw carried by the head and movable transversely thereof provided with a rack face, a pivoted handle carried by the head having teeth, certain of which are disposed in engagement with the rack face, whereby upon movement of the handle the sliding jaw will be actuated, a pivoted pawl carried by the frame arranged to engage certain other of the teeth formed on the movable handle, and spring means normally holding the pawl from out of engagement with said teeth, and means for permitting the manual moving of said pawl into engagement with said teeth.

FRANK THUERINGER.
